US0D1045510S

(12) **United States Design Patent** (10) **Patent No.:** **US D1,045,510 S**
(45) **Date of Patent:** **** Oct. 8, 2024**

(54) **CONTAINER**

(71) Applicant: **HANGZHOU GREAT STAR INDUSTRIAL CO., LTD.**, Hangzhou (CN)

(72) Inventor: **Yueming Li**, Hangzhou (CN)

(73) Assignee: **HANGZHOU GREAT STAR INDUSTRIAL CO., LTD.**, Hangzhou (CN)

(**) Term: **15 Years**

(21) Appl. No.: **35/516,823**

(22) Filed: **Mar. 3, 2023**

(80) **Hague Agreement Data**

Int. Filing Date: **Mar. 3, 2023**

Int. Reg. No.: **DM/227914**

Int. Reg. Date: **Mar. 3, 2023**

Int. Reg. Pub. Date: **Apr. 7, 2023**

(51) **LOC (14) Cl.** **07-01**

(52) **U.S. Cl.**

USPC **D7/510**

(58) **Field of Classification Search**

Primary Examiner — Andrew Kerr

Assistant Examiner — Courtney Clark-Rasheed

(57) **CLAIM**

The ornamental design for a container, as shown and described.

DESCRIPTION

1.1 is a front plan view of a container showing my new design;

1.2 is a left side elevational view thereof;

1.3 is a right side elevational view thereof;

1.4 is a top elevational view thereof;

1.5 is a bottom elevational view thereof;

1.6 is a right, front, top perspective view thereof;

1.7 is a right, front, top perspective view of the container in an opened state;

1.8 is a rear plan view thereof; and

1.9 is a left, front, top perspective view thereof.

The broken lines in the drawings depict portions of the container that form no part of the claimed design.

1 Claim, 9 Drawing Sheets
